E. F. CHAFFEE

SASH HOLDER

Filed Dec. 17, 1925

Patented Feb. 5, 1929.

1,701,140

UNITED STATES PATENT OFFICE.

EDWARD F. CHAFFEE, OF SYRACUSE, NEW YORK, ASSIGNOR TO THE O. M. EDWARDS COMPANY, INC., OF SYRACUSE, NEW YORK, A CORPORATION OF NEW YORK.

SASH HOLDER.

Application filed December 17, 1925. Serial No. 76,083.

This invention relates to window constructions and particularly to means for releasing the sash from snug engagement with the frame and the sill preliminary to lifting the 5 sash.

The invention consists in the novel features and in the combinations and constructions hereinafter set forth and claimed.

In describing this invention reference is 10 had to the accompanying drawings.

Figure 1 is a fragmentary front elevation of a window construction embodying this invention.

Figure 2 is a face sectional view on line 15 2—2 Figure 1.

Figure 3 is an interface view of the detached sash holder.

Figure 4 is an edge view of the detached sash holder, contiguous portions of the window and window frame being also shown. 20

This window construction comprises, generally, a window frame formed with a guide including the usual outer stop, a sash movable along the frame, a combined sash holder 25 and window releasing means arranged to normally force the sash toward the stop, and when operated preliminarily to lifting the sash, to force the sash away from the stop and away from the sill of the frame.

30 The invention further includes the construction of a combined sash holder and starter whereby the sash is moved at a right angle to its plane, when the sash holder and starter is operated to lift the sash off the sill.

35 One form of combined sash holder and releasing means in which the window sash is forced by the releasing means away from the window stop as well as lifted off the sill, is shown in my pending application Sr. No. 66,702, filed November 4, 1925. The numeral 1 designates the window frame having the usual outer stop 2 which forms part 40 of a guide 3 for the sash 4. The sash holder and releasing means comprises units located preferably at the inner lower corners of 45

the sash, each unit being of the general construction shown in my Patent No. 1,349,046, Oct. 10, 1920, and in my application Sr. No. 667,496, filed October 9, 1923, with the sash 50 releasing attachment of my present invention added thereto.

Each of the units comprises a base or housing 4 which encloses a recess 5 opening through the inner face of the housing 4.

55 The base is mounted on the sash in such

position as to close the open rear side of the recess. In addition the sash holder comprises a bolt 6 slidably mounted in the housing 4 and operated by the lever 7 pivoted at 8 in the housing 4 and having an angular arm 9 connected to the bolt to actuate it and also having a longer arm extending to the outside of the housing and normally arranged in juxtaposition to a stationary pinch handle 10 on the housing 7. Each bolt 6 is beveled as at 11 and is engaged or coacts with a rack on the stop 2, having a complementary bevel face 13, the bevel face 11 and 13 being so arranged that the bolt 6 of each sash lock when thrust outwardly by 70 its spring 14 forces the sash against the stop 2.

The construction per se of the sash holder thus far described is old in so far as this invention is concerned. Each of the sash 75 holder units 4 is provided with sash releasing means which is operated when the bolt 6 is withdrawn, and as here shown, this sash releasing means is actuated directly by lever 7.

The releasing means of each sash holder is a pusher rod 15 movable through a suitable passage in the lower edge of the housing 4 with its inner or upper end arranged in the path of the lever 7, and normally spaced 80 apart from such lever. This pusher 15 is here shown as movable vertically and as coacting with the sill at its lower end inclined plane fashion to force the sash away from the stop 2, toward which said sash is 85 moved by the beveling of the bolts 6. Preferably both the sill and the lower end of the pusher rods 15 are formed with inclined planes, and therefore the lower end of each rod 15 is beveled at 16 and coacts with a 90 complementary downwardly beveled face 17 on the sill. Usually the sill is provided with metal blocks 18 which form seats for the pushers 15, and these seats or beveled jaws 17 are formed on the blocks. 100

In operation after the operator takes hold of the levers 7 of the sash holders and presses them toward the pinch handles 10, the bolt 6 of each sash holder is withdrawn, thus 105 relieving the sash of the wedging force exerted by the bolts 6 tending to force the sash against the outer stop. After the bolts have been thus withdrawn the levers 7 engage the pusher rods 15 and force them 110 downwardly causing the lower beveled ends

of the rods to thrust against the bevel faces 17 on the blocks 18 on the sill, so that the sash is forced away from the window stops as well as forced upwardly.

5 What I claim is:—

1. In a window construction, the combination of a window frame formed with guides and with an outer stop, a sash movable along the guides and the stop, a sash holder 10 on the inner side of the sash and including a holding member and means extending along the guide and coacting with said member, the holding member and said means being constructed to force the sash 15 toward the outer stop, the sash holder further comprising means for operating the holding member and a sash release arranged to press against the sill of the frame and to be operated by the operating means 20 for the holding member, the releasing means and the sill being provided with faces arranged to act incline plane fashion on each other and force the sash away from the stop.

2. The window construction of claim 1 25 in which the sash release comprises a rod arranged to push downwardly toward the sill and in which the sill and the lower end of the rod are provided with such faces arranged to act incline plane fashion on each 30 other.

3. A sash holder comprising a casing, a holding member movable in the casing, a pusher movable downwardly in the casing toward the sill of the window frame, and an 35 operating member carried by the casing for actuating the holder member and the pusher, the pusher being provided with a bevel face at its lower end; in combination with a frame having means with which the holding mem-

ber coacts to press the sash against the window stop, the sill of the frame having means coacting with the beveled face of the pusher to withdraw the sash away from the stop when the operating member is actuated. 40

4. A sash holder comprising a casing, a sash holding member movable in the casing, a releasing member and an operating member carried by the carriage and arranged to actuate the holding member to withdraw it and at the same time operate the releasing member, the releasing member comprising a vertically slid able rod movable beyond the lower edge of the sash in combination with a window frame having means for coacting with the holding member 45 whereby the sash is pressed toward the window stop by the engagement of the holding member with said means, and the sill is provided with a bevel face arranged to 50 coact with the lower end of the rod to force the rod and the sill away from the stop when the operating member is actuated. 55

5. A sash holder comprising a casing, a holding member movable in the casing, a pusher movable downwardly in the casing toward the sill of the window frame, and an operating member carried by the casing for actuating the holder member and the pusher, means on the sill for coacting with the pusher, said means and the pusher having faces 60 arranged to act incline plane fashion to force the sash in a direction at an angle to the general plane of the sash. 65

In testimony whereof, I have hereunto signed my name, at Syracuse, in the county of Onondaga, and in the State of New York, this 7th day of December, 1925.

EDWARD F. CHAFFEE.
